UNITED STATES PATENT OFFICE.

JOSEPH SACHS, OF HARTFORD, CONNECTICUT.

CLIP.

1,204,691.

Specification of Letters Patent. Patented Nov. 14, 1916.

Application filed September 20, 1915. Serial No. 51,670.

To all whom it may concern:

Be it known that I, JOSEPH SACHS, a citizen of the United States, residing at Hartford, in the county of Hartford and State 5 of Connecticut, have invented certain new and useful Improvements in Clips, of which the following is a specification.

This invention relates to clips. A clip comprising the invention is susceptible of 10 general use, although it is of especial utility when used in connection with certain kinds of electric appliances, being of particular advantage when incorporated in a cut-out.

The primary purpose of the invention is 15 the provision of compact means by which a wire or equivalent can be clamped in a solid and substantial manner to the clip.

In the drawings accompanying and forming part of the present specification I have 20 shown in detail one form of embodiment of the invention which will be set forth fully in the following description. I do not limit myself to this disclosure; I may depart therefrom in several respects within the 25 scope of the invention defined by the claims following said description.

Referring to said drawings: Figure 1 is a 30 top plan view of a cut-out furnished with clips embodying the invention, the fuse of the cut-out being omitted. Fig. 2 is a side elevation partly in longitudinal section of said cut-out and clips. Fig. 3 is an end view of the same, the fuse being illustrated in position. Figs. 4 and 5 are sections on 35 the lines 4-4 and 5-5 respectively of Figs. 1 and 2, looking in the direction of the arrows.

Like characters denote like parts throughout the several views.

40 As intimated the improved clip is susceptible of general use. In the drawings I have shown a fuse cut-out, and this particular appliance is equipped with two of such clips adapted to receive a fuse, each clip as 45 will be clear being furnished with wire connecting means. The cut-out comprises a base as 2 and duplicate clips as 3 fastened to the base 2 in some convenient way, one of which will be hereinafter more particularly 50 described. It is usual to form the base or block 2 of insulating material; it may for instance consist of porcelain.

In conjunction with a suitable clip such as one of those denoted by 3, I provide wire 55 connecting means, the wire connecting means being within the clip by which compactness is insured. When I say "within,"

I mean to infer that the wire is inside the boundary or area of the clip rather than outside. While the wire connecting means can 60 be either interior or exterior of the clip I prefer that it be interior of the clip, thus further insuring compactness. A cut out of the inclosed fuse type as is understood usually comprises two clips for each fuse and by 65 connecting the wires to the clips within the clips, I can make the supporting body or base of the cut-out much shorter than is at present required in such appliances. By this I not only economize space but in so doing save stock 70 and decrease weight and also provide a very secure and efficient wire connecting means. The wire connecting means comprises a clamping member for clamping the wire to the clip. Preferably this wire clamping 75 member is disposed interiorly of the clip and is settable by the holding down means for the clip or parts or means cooperating therewith.

As the two clips 3 and their adjuncts are 80 of duplicate construction, a detailed description of one will apply to the other. Said clip 3 comprises the base portion 4 and lips as 5 and 6 extending outward therefrom, the lips and base being generally integral. The 85 clip can be made of resilient sheet metal to secure the necessary springiness of the co-acting lips. The block 2 has a cavity or depression 7 to receive the base portion 4, and the latter in turn has a seat or groove 90 as 8 in which a wire may be laid. This seat 8 is on the upper side of the base 4 and is practically at the junction of the base with the lip 6. Extending through the block 2 is a gromet 9, the head 10 of the gromet being 95 fitted in the counterbore or chamber 11 in the underside of the block and in the present instance bearing flatwise against the top wall of the chamber or counterbore. The base 4 of the clip has an approximately central perforation or hole to receive the outer portion of the gromet, the outer or upper end of said gromet being headed or expanded over the upper surface of the base as at 12. This is one of several advantageous 105 ways in which the clip 3 can be securely connected with the block 2 or equivalent.

The gromet 9 is interiorly threaded to receive the wire clamping screw 13 which as 110 illustrated has a plain cylindrical portion between its threaded part and head. The screw 13 constituting one convenient and advantageous means for operating a suitable wire-clamping member has the washer 14 made

for instance from sheet metal. The clamping member or washer 14 has in it an opening or hole 15 which originally is of circular form and of a diameter greater than the 5 threaded part of the screw 13, by reason of which the washer can be passed over the threaded portion of the screw until it receives the plain portion thereof. When the two parts are thus assembled, the washer 10 will be contracted between its ends so that the hole 15 therein will be shaped to approximate oval form as indicated in Fig. 5, the transverse diameter of the oval or elongated hole 15 being less than the diameter of the 15 threaded portion of the screw, so that when the washer is thus contracted, it cannot be accidentally separated from the screw, the threaded portion and head of the screw preventing this condition. As will be apparent 20 the upper end of the threaded portion of the screw presents a shoulder for the washer. The hole 15, it will be noted, is elongated in the direction of the length of the clamping member or washer 15, and in a direction 25 transversely of the co-operating clip 3. The clamping member or washer after being positioned within the clip, cannot turn, it being held against turning by the lips 5 and 6 of the clip. Being, however, held to the 30 screw 13 the clamping washer 15 will be moved toward or away from the upper side of the base portion 4 of the clip as the screw is screwed into or out of the gromet 9. It will be clear that while the washer rises or lowers with the turning of the screw, the latter turns loosely in the washer. As will be apparent the washer is susceptible of movement 35 transversely of the clip 3 and there is an advantage in this, in that said washer can be brought into clamping relation with the wire irrespective of its size (within limits), and irregularities therein, the washer owing 40 to the movement in question automatically adapting itself to the form of the wire while the screw 13 is being set. The operative end 45 of the clamping member or washer 14 has on its inner side the seat or groove 16 complementary to the seat or groove 8.

From what has been noted the manner of 50 connecting a wire will probably be readily understood, but I deem it desirable to briefly set forth the same. Initially the screw 13 and washer 14 will be in the retracted positions thereof, for instance as shown in Fig. 4. 55 In this event the wire will be laid in the seat or groove 8 and the screw 13 driven home. The head of the screw acting against the washer 14 will cause said washer to bind upon the wire to press the same firmly in the seat 8, the washer if necessary moving laterally of the clip to automatically conform 60 itself to the particular wire being used. In contracting the washer 14 in the manner set

forth the same is inset slightly as at 17 in opposite sides thereof thus elongating the 65 hole 15 as shown in Fig. 2. It will be noted that while the wire has been clamped within the body of the fuse clip, yet there is ample room for the insertion of the inclosed fuse into the contacting lips of the clip between 70 which lips the wire clamping means is positioned, while at the same time the wire clamping screw cannot be manipulated after 75 it has been set to clamp the wire as long as the fuse is in place.

It will be remembered that the clip has a wire seat 8 extending longitudinally at one side thereof as shown. The formation of this wire channel or groove it will be observed produces a projection exteriorly of 80 the clip and this projection performs an important function being adapted to fit within a cavity or opening in a block or the like and thus effectually prevent the clip from turning.

What I claim is:

1. A clip comprising a base and resilient fuse engaging lips extending from said base, said base having inside the clip a wire receiving groove and having exteriorly of the 90 base a corresponding projection to prevent the clip from turning on a support.

2. A clip comprising a base and resilient fuse engaging lips extending from said base, the base having a pressed in wire receiving 95 groove and a pressed out projection, the latter to prevent turning of the clip on its support.

3. A clip comprising a base and resilient fuse engaging lips extending from said base, holding-down means for the clip, engaging 100 the base, a clamping member between the lips and means for setting the clamping member having an operating connection with said holding down means, said base and said 105 clamping member having complementary grooves to receive a wire.

4. A clip comprising a base and resilient fuse engaging lips extending from the base, said base having an aperture and also having a longitudinally extending wire receiving groove at one side of the aperture, holding-down means for the clip, extending through said aperture, a clamping member between said lips and having a wire receiving 110 groove complementary to said other groove and means for setting said clamping member, having an operating connection with said holding-down means.

In testimony whereof I affix my signature 115 in presence of two witnesses.

JOSEPH SACHS.
